UNITED STATES PATENT OFFICE.

JOHN T. DOWNEY AND GEORGE P. FUNKHOUSER, OF PLATTSBURG, MISSOURI.

ATTACHMENT FOR CULTIVATOR-SHIELDS.

SPECIFICATION forming part of Letters Patent No. 393,099, dated November 20, 1888.

Application filed August 21, 1888. Serial No. 283,337. (No model.)

To all whom it may concern:

Be it known that we, JOHN T. DOWNEY and GEORGE P. FUNKHOUSER, of Plattsburg, in the county of Clinton and State of Missouri, have invented a new and Improved Attachment for Cultivator-Shields, of which the following is a full, clear, and exact description.

Our invention relates to an attachment for cultivator-shields, and has for its object to provide a means whereby the attachment may be readily connected to the arch of the cultivator, whether the same be vertical or horizontal; and the further object of the invention is to provide a means whereby the shield may be carried to the right or the left, as desired, and raised or lowered to any height required by the condition of the ground.

The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a side elevation of the cultivator-shield and attachment partially in section, the cultivator being illustrated in vertical section in dotted lines. Fig. 2 is a plan view of the said shield and the attachment, the cultivator being in dotted lines and the axle in section; and Fig. 3 is an end view of the shield and attachment also of the cultivator.

In carrying out the invention, A represents a cultivator-shield, which may be of any approved construction, and B a divided tongue pivoted to the forward end of the said shield, as best shown in Figs. 1 and 2. The tongue B, which may be constructed of either wood or metal, consists, preferably, of a long section, b, and a short section, b'.

Each end of the long section b is provided with an eye, b², the eye in the rear end being adapted to receive a bolt passing through the shield, whereby the connection between the shield and the tongue is effected, and the forward eye is purposed to engage with a similar eye, b³, formed at the end of the short section b', which section is also provided with an eye at its opposite end.

The arch D of the cultivator, which is rep-

resented in dotted lines in the drawings, is adapted to be embraced by two independent metal clamps, D', which clamps are preferably constructed of strap-iron, having one end bent 55 upon itself to form the hook d.

When the hooks are made to engage with the arch of the cultivator, the extremity of the hook and the body are united through the medium of a bolt or bolts provided with suitable 60 nuts, as best shown in Figs. 2 and 3, and the hooks are held in place by set-screws d'.

To each of the clamps D', at the extremity of the body, a horizontally-slotted plate, E, is attached, adapted to project outward from 65 the body of the hook, in essentially the same plane therewith. The slots of the plates E are produced in the side and extend through the same, the plates of each clamp being preferably of the same length.

Instead of employing a plate and slotting the same, a piece of stout wire or rod metal may be bent upon itself to form a link, and the said link is attached to the clamp in any approved manner, as best illustrated in Fig. 2. 75

A threaded rod, H, is passed through the slots of the plates or links E after they have been placed one upon the other, and the said plates or links are held essentially in contact by nuts h, entered upon the said screw-rod at 80 each side of the plates, as best shown in Figs. 1 and 3.

The screw-rod H is provided at one end with an eye adapted to interlock with the outer eye in the short section b' of the tongue B. 85

It will thus be observed that by adjusting the nuts h on the plates or links E the threaded rod H may be raised or lowered in the said plates in a convenient and expeditious manner, whereby the shield may through the medium of the tongue B be also raised or lowered to any desired height required by the condition of the ground, and the said adjustment also permits the shield to be attached to various styles of cultivators, and by reason of the 90 divided tongue B the said shield may be adjusted to either side or be set to travel between the wheels of the cultivator.

Having thus described our invention, what we claim as new, and desire to secure by Letters Patent, is—

1. The combination, with a cultivator-

shield and a pivoted sectional tongue attached thereto, of clamps adapted for attachment to the arch of the cultivator, slotted plates or links secured to the extremity of the said clamps, and 5 a threaded rod passing through the said slotted plates pivoted to the tongue and provided with lock-nuts engaging the outer faces of the said plates, substantially as shown and described.

10 2. The combination, with a cultivator-shield and a sectional pivoted tongue attached thereto, of clamps consisting of a piece of metal bent to a hook shape at one end and provided with a bolt uniting the extremity of the hook

15 and the body of the clamp, a longitudinal slotted plate or link secured to the lower end of the clamp, a threaded bolt passing through the said plate pivoted to the tongue, and lock-nuts engaging the outer surface of the said slotted plate, substantially as shown and described, whereby the shield may be adjusted vertically and laterally, as and for the purpose specified.

JOHN T. DOWNEY.

GEORGE P. FUNKHOUSER.
